UNITED STATES PATENT OFFICE.

ARCHIE NOEL JETTE, OF ANACONDA, MONTANA.

SMEILING FURNACE.

Original application filed August 10, 1920. Serial No. 402,556. Divided and this application filed January 3, 1921. Serial No. 434,759.

To all whom it may concern:

Be it known that I, ARCHIE NOEL JETTE, a citizen of the United States, residing at Anaconda, in the county of Deerlodge and

5 State of Montana, have invented certain new and useful Improvements in Smelting Furnaces, of which the following is a specification.

This invention relates to metallurgical 10 smelting furnaces of the reverberatory type and in particular to reverberatory copper smelting furnaces.

The improvement constituting the invention consists essentially of a cast iron plate 15 so constructed and arranged as to provide a furnace with a replaceable tap hole and skimming block, water-cooled to insure permanency.

Experience has shown that with the ordinary and usual construction that portion of 20 the wall through which the tapping and skimming is done is subject to rapid wear and tear from the operations due to the action of the effects of the hot molten metal, necessitating frequent repair and causing 25 frequent interruptions and delay in the furnace operations.

It is, furthermore, not an uncommon occurrence that the hot bath breaks through 30 the wall as ordinarily constructed.

To avoid the above dangers and inconveniences I propose the use of a plate of the form and character to be hereinafter described.

35 Having reference to the drawings, which form a part of the specification,

Fig. 1 is a front view of an arrangement embodying the invention;

Fig. 2 is a section on line 2—2, Fig. 1; 40 Fig. 3 is a section on line 3—3, Fig. 1; and

Figs. 4 and 5 are a plan view and a side elevation of a slag launder.

As shown in Figs. 1, 2 and 3, a cast iron plate 1 is set in the masonry at the end of 45 the furnace, a system of water-cooling pipes 2 being embedded therein.

The plate 1 extends across the whole width of the part of the furnace at which the matte is collected and has preferably two tapping 50 holes 3 and 4, either one may be used in case the other becomes clogged or frozen up.

Each tap hole is provided with an apertured tap-hole block 5 held in place by wedges 6 passing through apertured lugs 7 55 on the plate 1.

Should the aperture in the tap-hole block become burnt out or enlarged to too great a degree, the wedges can be knocked out and a new block quickly and simply installed.

Above the plate 1 is located the skimming block 8, provided with a gate 9. Through the opening 10 fluid slag is withdrawn.

To facilitate the removal of the slag which flows from the furnace over the skimming block, I provide the outer end of the block with a semi-cylindrical groove portion 11 into which fits a correspondingly shaped tongue 12 at the end of a section of the slag launder 13. The launder is composed of a 60 plurality of sections each of which has one end provided with a groove and the other with a tongue corresponding to the portions 11 and 12 respectively, to form a continuous trough.

75 The sections are preferably curved, as shown in Figs. 4 and 5, so that the slag may be delivered to one side of the furnace.

By the arrangement described the tap-hole blocks and the skimming block or any 80 section thereof may be easily removed.

By virtue of the tap-hole plate it is possible to use a much deeper molten metal reservoir with greater safety against break-outs. It is instrumental in obtaining a 85 continuous furnace operation to the end of the furnace campaign without interruptions of the kind above referred to.

It should also be noted that the junction 90 between the launder and the furnace proper provides for a stable connection, by utilizing the water-cooled plate 1 as an anchorage.

The arrangement described not only affords a good, strong and simple installation, but it brings the launder above the 95 floor level so that there exists an air space completely around the launder eliminating the necessity of excavation and, what is even more important, allows the heat to radiate off, thereby insuring a longer life. The cast iron of the launder is protected from the molten slag by any form of lining such as brick, fire clay or any other suitable material.

100 This application is a division of my application Serial No. 402,556, filed August 10, 1920.

I claim:

1. In a reverberatory furnace, a cast-iron plate having a tap-hole and a recess in the 110

front thereof, a tap-hole block seated in the said recess and means for detachably securing the block in the recess.

2. In a reverberatory furnace having a slag outlet, a tap-hole plate below the said outlet and a skimming block in said outlet anchored upon the upper edge of the tap-hole plate.

3. In a reverberatory furnace having a slag outlet, a water-cooled tap-hole plate below the said outlet and a skimming block in said outlet anchored upon the upper edge of the tap-hole plate.

4. In a reverberatory furnace a slag launder comprising a plurality of sections interconnected by peripheral groove and tongue connections. 15

5. In a reverberatory furnace having a slag outlet, a water-cooled tap-hole plate below the outlet, a skimming block in the outlet anchored upon the tap-hole plate and a sectional slag launder having its first section detachably connected to the skimming block. 20

In testimony whereof, I affix my signature.

ARCHIE NOEL JETTE.
